[57] CLAIM

The ornamental design for a utility hook, substantially
as shown and described.

DESCRIPTION

FIG. 1 is a reduced perspective view of the utility hook
showing my new design;

FIG. 2 is a top plan view thereof;

FIG. 3 is a side elevational view thereof;

FIG. 4 is an end elevational view taken from the left of
FIG. 3; and

FIG. 5 is an end elevational view taken from the right of
FIG. 3.

FIG. 1.FIG. 2.FIG. 3.FIG. 4.FIG. 5.
